Just Fur Them Pet Urns—Pet Urn with Picture Frame, Perfect Pet Memorial Gift or Dog Memorial Gift for Grieving Pet Lover, Dog Urn or Cat Urn for Pet Ashes for the Garden as a Dog Memorial Stone. 5 pages copy found at Amazon.com https://www.amazon.com/dp/B089RGW1WT?pd_rd_i=B089R6W1WT&pd_rd_w=V3Hdk&pf_rd_p=4a33be0c-5de3-47f0-828b-e64e836b17dc&pd_rd_Year=2021.*

Primary Examiner — Paula Allen Greene(74) Attorney, Agent, or Firm — Eric Karich; Karich & Associates(57) CLAIM

The ornamental design for a pet memorial urn, as shown and described.

DESCRIPTION

FIG. 1 is a perspective view of a pet memorial urn, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines to the animal figure and the logo depict environment and forms no part of the claimed design.

1 Claim, 3 Drawing Sheets(56)
